DESIGN FOR AN INDEX PLATE FOR CHECK WRITERS

John P. Hunter, East Orange, N. J., assignor to
Safeguard, Inc., New York, N. Y., a corporation
of Delaware

Application February 23, 1935, Serial No. 55,585

Term of patent 7 years

To all whom it may concern:

Be it known that I, John P. Hunter, a citizen
of the United States, residing in East Orange,
N. J., 25 North Harrison Street, have invented
a new, original, and ornamental Design for an
Index Plate for Check Writers, of which the fol-
lowing is a specification, reference being had to
the accompanying drawing, forming part thereof,
in which:

Figure 1 is a plan view, and
Fig. 2 is a sectional view on the line 2—2,
Fig. 1, of the index plate for check writers.

I claim:

The ornamental design for an index plate for
check writers, substantially as shown.

JOHN P. HUNTER.
